RAMP STRUCTURE

Application filed June 12, 1929. Serial No. 370,227.

This invention relates to ramps for garages and has for its object to provide a ramp structure which is particularly adaptable for giving ready access to the basement floors beneath the main entrance floors as well as to the upper floors.

In my co-pending application, Ser. No. 151,754 filed November 30, 1926, I have disclosed a ramp structure consisting essentially of two entwined spirals, one ramp serving for up-going traffic and the other for down traffic. This ramp is entirely satisfactory for garages in which the main entrance floor is the ground floor, for in such case the down-coming traffic leaves the ramp and all up-going traffic enters the ramp at the bottom floor, so that there is no cross traffic on the main floor. In like manner on the upper floors substantially all the cars leave the ramp and enter the floors from the up-going spiral and leave the floors by the down-going spiral, there being of course very little traffic from one upper floor to another in the garage.

When, however, there are several basement floors below the main entrance floor the continuous ramp structure disclosed in my prior application extending from the bottom floor to the top of the building is not altogether satisfactory for the reason that cars entering the ramp to go to one of the basement floors have to enter at the same point that the outgoing cars from the upper floors leave the ramp, thus producing considerable cross-traffic and confusion on the main floor of the garage.

My improved ramp structure disclosed in the present application is designed to take care of this situation and eliminate cross traffic at the main floor.

In the accompanying drawings I have illustrated a preferred embodiment of my invention, and in the said drawings,

Fig. 1 is a plan view of the main floor;

Fig. 2 is a plan view of the floor above the main floor;

Fig. 3 is a vertical section of the ramp;

Fig. 3^a is a diagrammatic development of the ramp structure;

Figs. 4 and 5 are diagrammatic views illustrating the position of the wheels of the cars

on the up and down ramps, respectively; and

Figs. 6 and 7 are sectional views showing a typical banking of the up and down ramps, respectively.

Referring to the drawings, 1 indicates the main floor of the garage which in a typical example will have three floors above the main floor and two basement floors. To serve the upper floors I provide a spiral ramp structure such as shown in my co-pending application, except for the floor contour of the driveway which is different on the two ramps, as will be later described.

The two ramps 2 and 3 which serve the upper floors are inclined after the manner of a left-hand screw. That is, the ascending cars turn continuously to the right going up the ramp, while the descending cars turn continuously to the left in coming down the ramp. It will be understood that each ramp rises the distance of a single floor at each half turn, so that there is an opening from each floor to each ramp. The openings are diametrically opposite as indicated at 4 and 5 in Fig. 2, the opening designated 4 being the entrance to the down-going ramp on the particular floor illustrated, while the opening 5 is the exit from the up-going ramp.

On the main entrance floor the entrance and exit 4^a and 5^a respectively, for the ramps leading to the upper part of the building are preferably extended somewhat beyond the circumference of the ramp by means of curbing 6 as indicated in Fig. 1. The curbing which constitutes a continuation of the inner wall of the ramp serves to separate the entrance 4^a to the up-going ramp from the entrance 7 of a ramp 8 leading to the basement floors. In the same way the curbing 6^a which constitutes a continuation of the other half of the inner wall of the ramp serves to separate the exit 5^a of the down-going ramp from the upper floors from the exit 9 of a ramp 10 extending up from the basement. The ramps 8 and 10 are preferably the same diameter as the ramps 3 and 4, and except at the main floor form continuations of the ramps 3 and 4, respectively, except for the difference in contour of the surface.

By the entrance and exit arrangement at

the first floor, the direction of traffic on the ramps serving the basement floors is reversed. That is to say, the cars turn continuously to the left going down the ramp and turn continuously to the right coming up the ramp. By this arrangement the entrance to the ramp structure for all incoming traffic, whether going up or down, is on one side of the ramp, and the exit for all outgoing traffic is on the opposite side of the ramp, and confusion and cross traffic are avoided.

As stated above, the surface contour of the ramp for up-going traffic will not be the same as for down-going traffic, for the reason that a ramp banked to correct for torsional strains incident to the different levels of the wheels of the car going up the ramp will aggravate those strains in a car proceeding down the ramp. It is common to bank the ramps to compensate for the centrifugal force of the cars traveling up and down the ramp, and a factor for centrifugal force is included in determining the contour of the ramps. According to my invention both ramps are raised or banked toward the outer periphery but in different degrees, and also to different contours.

Figs. 6 and 7 show typical cross sections of the up-going ramps 3 and 10 and the down-going ramps 2 and 8, respectively, each contour containing also a factor of several inches to compensate for centrifugal force. On both of these ramps a car of 126-inch wheel base which is taken as the average, following the middle line of the ramp, will be free of any torsional strain on its frame. That is to say, with all four wheels in contact with the surface of the ramp all parts of the chassis will lie in the same plane with equal compression of the springs.

In Fig. 4 I have illustrated diagrammatically a half turn of a ramp of ten foot rise between floors with a car 11 placed upon it, and going up the ramp. The car 11 has its rear wheels on the radius line of the ramp at a point one foot up the ramp. The inner rear wheel is traveling on the arc marked 12 and the outer rear wheel on the arc marked 13. The front wheels of the car will not, however, be on the same radius line because the axle of the car is fixed and the wheels are turned on the axis of the steering knuckles as indicated, so that the inner front wheel is farther advanced up the ramp than the outer front wheel. Thus the inner front wheel will be on the radius line corresponding to an elevation 2 ft. 6 in. above the floor level, whereas the outer front wheel will be on the radius line 2 ft. 3 in. up the ramp. If the car were perfectly rigid and the ramp not banked, that is, level on its radius lines, the car would be supported by the two back wheels and the inner front wheel, and the outer front wheel would be three inches off the surface of the ramp. To compensate for this the contour

of the ramp is banked on a curve as indicated in Fig. 6. As here shown, a factor of five inches for the width of the car is allowed for centrifugal force. The ramp is level so far as inclination in a radial direction is concerned out to a point beyond the path of the inner rear wheel, which is indicated by line 12. The path of the outer rear wheel is indicated by line 13 and the surface of the ramp is elevated five inches at this point to compensate for the centrifugal force, no other factor entering into the computation for the rear wheels for the reason that they are on the same radius line as the car moves up the ramp.

The path of the inner front wheel is indicated at line 15, and at this point the ramp will preferably be banked to the extent of one inch elevation in order that the curved surface shall not be too abrupt. The path of the outer front wheel is indicated at line 16. To compensate for five inches factor for centrifugal force alone this point of the ramp should be banked to a height of six inches, but as this wheel is three inches lower than the other front wheel, due to its being back of the other front wheel in the progress of the car up the ramp, it is necessary at this point to add a factor of three inches, making the elevation at this point in the ramp nine inches above the path of travel of the inner rear wheel. That is to say, the point X on the radius line 2 ft. 3 in. in Fig. 4 is nine inches higher above the floor line than the point Y at the intersection of this radius line and the line of travel of the inner rear wheel.

With a car of the relative dimensions indicated traveling along the path indicated, there will be no torsional strains on the frame of the car. With cars of other dimensions there will of course be slight torsional strains, but such strains are very much minimized in cars of all sizes by shaping the ramp for a car of mean dimensions.

The contour for the down ramp is determined in the same fashion, but in this case the inner rear wheel is farther down the ramp than the outer rear wheel so that if the car were rigid it would be the inner front wheel which would be out of contact with the surface of the ramp were the latter level. In the down ramp the intersection of the radius line with the ramp surface forms a slightly convex line instead of a concave line, as in the case of the up ramp. Thus in Fig. 5 the path of the inner rear wheel is indicated by line 17 which has an elevation of two inches above the extreme inner edge of the radius. The outer rear wheel moves along the line 18 which is at an elevation of ten inches, thereby allowing an eight inch factor for centrifugal force. A greater factor for centrifugal force is preferably provided on the down ramp because the necessity for checking the speed of the cars is obviously greater.

The inner front wheel is shown as traveling on the circumferential line 19 and with the rear wheels on the radius line which is nine feet from the lower floor. This wheel, in the case of the car illustrated, will be on the 7 ft. 6 in. radius line, whereas the outer front wheel which travels on the circumferential line 20 will be on the 7 ft. 9 in. radius line. Hence, if we assume that the frame of the car is perfectly rigid and the axles fixed with regard thereto, the car would be supported on the two rear wheels and the outer front wheel, with the inner front wheel three inches from the surface of the ramp, whereas in the ascending car it is the outer front wheel which would be out of contact with the ramp surface were the car rigid. To compensate for this the down-going ramp is shaped to provide a greater elevation for the inner front wheel than would be required to merely compensate for the centrifugal force of the cars traveling in a curved path. Thus, in the example shown the surface of the ramp for the inner front wheel is seven inches above the floor level, while the surface of the ramp along the line 20 is twelve inches above the floor level.

The specific figures which have just been given are of course merely by way of example, and the ramp contours illustrated will vary with cars of different wheel base and with different factors allowed for centrifugal force. Also, of course, while the cars in traveling up and down the ramp generally follow the middle line of the ramp, it is not desirable to have them restricted to a narrower path of travel than the width of the ramp permits. Consequently to best adapt the entire ramp surface to the travel of the cars the exact figures determined for a car following the middle line of the ramp are modified to such extent as may be necessary to give a smooth roadway over the entire width of the ramp.

In applying this principle to the particular ramp of the present application, the surface of the ramp 2, which is the down ramp for the upper floors, will be given a contour corresponding to Fig. 7, whereas the ramp 10 which constitutes a continuation of the ramp 2 except for the dividing curb 6^a, will have a surface contour corresponding to Fig. 6 because it constitutes the ramp for cars ascending from the basement floors.

In certain of the following claims the contour of the ramp is described in terms of the paths of travel of the wheels of an automobile proceeding along the ramp, and it is to be understood that the path of the inner front wheel is substantially that portion somewhat less than one-quarter of the total width of the ramp lying immediately within the middle line of the ramp, that the path of the outer rear wheel is the corresponding portion lying immediately without the middle

line of the ramp, and that the paths of travel of the inner rear wheel and outer front wheel represent the balance of the ramp surface adjacent its inner circumference and its outer circumference, respectively. If the radius of the ramp is larger than necessary to give ample clearance on both sides to the cars proceeding along it, it may be advisable to shift the line between the paths of travel of the two inner wheels outwardly from the middle line of the ramp as the grade is easier near the outer circumference of the ramp.

I claim:

1. In a garage building, a spiral ramp providing a one-way passageway from floor to floor thereof, said ramp having its surface concave in radial cross section, the degree of concavity being proportional to the grade of the ramp so as to maintain the points of contact of the four wheels of a car of average dimensions traveling up the middle line of the ramp in the same plane.

2. In a garage building, a spiral ramp providing a one-way passageway from floor to floor thereof, said ramp having its surface convex in radial cross section, the degree of convexity being proportional to the grade of the ramp so as to maintain the points of contact of the four wheels of a car of average dimensions traveling down the middle line of the ramp in the same plane.

3. In a garage building, a ramp structure comprising spiral ramps, one of said ramps having its surface concave in radial cross section, the degree of concavity being proportional to the grade of the ramp so as to maintain the points of contact of the four wheels with the surface of the ramp in substantially the same plane in moving up the ramp, the other ramp having its surface convex in radial cross section, the degree of convexity being proportional to the grade of the ramp so to maintain the points of contact of the four wheels of the car with the ramp surface substantially in the same plane while moving down the ramp.

4. A garage building having a main floor and car storage floors both above and below said main floor, and a ramp for giving access to said floors, said ramp comprising entwined spiral passageways, one of said passageways having its surface from the main floor upwardly shaped to compensate for torsional strains in the cars moving up the ramp and its surface in the portion leading from the main floor downwardly shaped to compensate for torsional strains in cars moving down the ramp, the other spiral passageway having its portions above and below the main floor level shaped like the opposite portions of the other ramp.

5. A garage building having a main floor and car storage floors both above and below said main floor, a ramp for giving access to said floors, said ramp comprising entwined

5 spiral passageways, one of said passageways having its surface from the main floor upwardly shaped to compensate for torsional strains in the cars moving up the ramp and its surface in the portion leading from the main floor downwardly shaped to compensate for torsional strains in cars moving down the ramp, the other spiral passageway having its portions above and below the main floor 10 level shaped like the opposite portions of the other ramp, and a barrier across each ramp at the main floor in line with the passageway connecting the ramp with the floor to facilitate the reversal of traffic on the ramp 15 at the main floor.

6. A garage building having a main floor provided with doorways for the ingress and egress of automobiles, floors for the storage of cars both above and below said main floor, 20 a ramp structure connecting the main floor with the storage floors both above and below, said ramp structure comprising superior-posed entwined spiral roadways having passageways from each roadway to each floor of 25 the building including the main floor, and additional passages between each roadway and the main floor of the building, said passages being alongside each other and provided with car-guiding means whereby cars passing 30 along the additional passageways are directed in the opposite direction vertically with respect to cars passing along the first-mentioned passageways.

7. A garage building having a main floor 35 provided with doorways for the ingress and egress of automobiles, floors for the storage of cars both above and below said main floor, a ramp structure connecting the main floor with the storage floors both above and below, 40 said ramp structure comprising superim- posed entwined spiral roadways having pas- sages from each roadway to each floor of the building including the main floor, and additional passages between each roadway and the main floor of the building, and a barrier across each roadway at the main floor for separating said passages and preventing the 45 continuous passage of a car along the road- way past the level of the main floor.

8. In a garage building, a spiral ramp for 50 ascending cars having the contour of its sur- face such that a line extending from the axis of the spiral and intersecting the surface of the ramp at points in the paths of travel of the two front wheels of the ascending car has an angle to the horizontal greater than 55 a line extending from the axis of the spiral and intersecting the surface at points within the paths of travel of the two rear wheels.

9. In a garage building, a spiral ramp for 60 descending cars having the contour of its surface such that a line extending from the axis of the spiral and intersecting the surface of the ramp at points in the paths of travel of the two front wheels of the descending 65

car has an angle to the horizontal less than a line extending from the axis of the spiral and intersecting the surface at points within the paths of travel of the two rear wheels.

10. In a garage building, a ramp structure 70 comprising two entwined spirals, one for ascending cars having the contour of its sur- face such that a line extending from the axis of the spiral and intersecting the surface of the ramp at points in the paths of travel of the two front wheels of the ascending car has an angle to the horizontal greater than a line extending from the axis of the spiral and intersecting the surface at points within the paths of travel of the two rear wheels, and 75 one for descending cars having the contour of its surface such that a line extending from the axis of the spiral and intersecting the surface of the ramp at points in the paths of travel of the two front wheels of the descend- 80 ing car has an angle to the horizontal less than a line extending from the axis of the spiral and intersecting the surface at points within the paths of travel of the two rear wheels.

90 In testimony whereof I affix my signature.
